HAND REEL FOR ANTENNAS

William P. Lear, Dayton, Ohio, assignor, by mesne assignments, to Lear Avia, Inc., Piqua, Ohio, a corporation of Illinois

Application October 25, 1939, Serial No. 301,096

10 Claims. (Cl. 242—99)

This invention relates to antenna reels for aircraft radio communication apparatus, and more particularly relates to improved manual reels for wire antennae.

In accordance with my present invention I contemplate a novel foolproof hand reel particularly useful for a busy aircraft pilot. My novel reel minimizes danger of antenna wire breakage, and permits rapid efficient reeling and unreeling of the antenna wire. Tension or compression springs are eliminated in its construction. A brake is arranged to decelerate the reel from unwinding conditions to permit engagement of the ratchet without danger of stripping. The stationary or rest position for the reel is with the ratchet and brake both engaged, insuring a positive stop for the antenna wire in any degree of extension.

Another important feature of my present invention resides in the provision of a shift member arranged to operate the ratchet and brake in proper sequence preliminary to reeling-out, reeling-in or rest positions of the reel. The construction of my novel reel incorporates these features in a relatively small bulk. The shift member has four positions. Its movements are made relatively short. The sequence of the shifting operations is such as to disengage the brake just prior to both reeling-in and reeling-out, and to engage it during two steps intermediate between the reeling-out and reeling-in positions. The intermediate positions correspond to the engagement and disengagement of the pawl and ratchet device as will be hereinafter described in detail.

It is accordingly an object of my present invention to provide a novel hand reel.

Another object of the invention is to provide a novel hand reel for an antenna wire incorporating a pawl, a ratchet and a friction brake.

Still another object of the present invention is to provide a compact hand reel insuring proper deceleration of winding by means of a brake and associated shift-over member during changes between the reeling-in, reeling-out and rest positions.

A further object of the present invention is to provide a novel hand reel incorporating a deceleration brake engageable with a relatively short movement and coacting with a pawl and ratchet for controlling the reel proper.

Still a further object of the invention is to provide a novel hand reel for a wire antenna aboard an aircraft of compact and reliable construction, and readily operable by the pilot.

These and further objects of the invention will readily become apparent from the following description of a particular embodiment thereof illustrated in the drawings, in which:

5 Fig. 1 is an elevational view of the hand reel embodiment.

Fig. 2 is a plan view of the reel, showing the shift-over member.

Fig. 3 is a horizontal cross-sectional view through the reel showing the control mechanism, as taken along the line 3—3 of Fig. 1.

Fig. 4 is a vertical cross-sectional view through the braking, ratchet, and shift-over members, taken along the line 4—4 of Fig. 3.

15 Fig. 5 is a vertical cross-sectional view through the shift-over and braking mechanism of the reel, taken along the line 5—5 of Fig. 4.

Fig. 6 is a partial sectional view illustrating the pawl and ratchet arrangement of the reel, taken 20 along the line 6—6 of Fig. 3.

A preferred form which the hand reel of the invention may assume in practice is illustrated in the figures, Figs. 1 and 2 of which are elevational and plan views respectively. The antenna wire 20 is wound on the reel proper which comprises disks 10, 11 spaced by members 12. Spacer screws 15 secure disks 10 and 11 with spacers 12. Disks 10, 11 and spacers 12 are formed of insulation material for electrically isolating the antenna wire from the reel control mechanism and adjacent structures. "Micarta" with a linen base is suitable material for these reel parts. Reel crank handle 16 is attached by bracket 17 to outer reel disk 11. Handle 16 is 25 foldable on bracket 17 at pivot 18. The handle is folded towards disk 11 for safe positioning, particularly during free reeling-out operation.

Antenna wire 20 is attached to the end 21 of strap 22, the other end 23 of which is secured to 30 one of the spacers, 12a. Strap 22 is made of durable flexible material, such as strong fabric. End portions 21 and 23 of the strap are made up of pairs of metallic plates riveted together with the fabric strap 22 between. Electrical contact with reelable wire 20 is made in a 35 suitable manner, such as by rollers 25, 25 spaced from the reel. Electrical connection to the radio apparatus is effected through lead 26 to rollers 25. A lead weight, generally streamline, is secured at the outer or tail end of antenna wire 20 to insure extension of the wire in taut relationship beneath the aircraft in flight. Such attachment is general, and is for example described in my Patent No. 2,272,213 for "Antenna reeling 45 system."

In accordance with my present invention, reeling-in of an extended antenna portion is accomplished by manually cranking the reel by handle 16. A pawl and ratchet is incorporated in the reel to hold it at the position where the reeling-in is stopped. The weight at the free end of the wire keeps the remaining extended portion taut outside the aircraft. Means are also provided to disengage the ratchet from its pawl to permit free reeling-out of the wire when required. The weight at the outside antenna end effects rapid extension of the antenna wire when the ratchet is so disengaged. The ratchet is automatically reengaged with its pawl for the rest position of the reel, holding it against further unwinding after the proper wire length has been extended.

Further in accordance with the present invention, a friction brake is arranged to be applied prior to the engagement of the pawl and ratchet in order to decelerate the reel when rotating, to prevent stripping of the ratchet, and to avoid snapping of the antenna wire. A shift arrangement is incorporated with the reel control mechanism to insure application of the brake prior to engagement of the pawl and ratchet. The rest position of the reel corresponds to the position of the shift member which causes engagement of both the brake and the ratchet. When the shift member is moved to "reeling-in," the ratchet becomes engaged and the brake disengaged, as will be hereinafter shown.

Referring now to Fig. 3, which is a horizontal cross-sectional view through the reel and control mechanism taken along the line 3-3 of Fig. 1, we note that the reel is rotatably mounted with respect to an extension 27 projecting centrally from base 28 of housing 30 for the control mechanism of the reel. Housing 30 is attached to base 31, which is in turn secured to the aircraft in a suitable position near the pilot. Reel hub 32 is secured to disks 10, 11 by bolts 33. Reel hub 32 is mounted concentrically with brake hub 35 and is secured thereto for rotation therewith by a key comprising rectangular strip 36 recessed into outer disk 11, and screws 37. Hubs 32 and 35 are preferably made of an aluminum alloy. Brake hub 35 is mounted for free rotation with respect to projecting rod 27; a graphite oil-impregnated bearing or liner 38 being interposed therein, preferably made of a Bakelite material having a linen base.

Brake hub 35 is secured to a metallic disk 40 by screws 41 as shown in Figs. 3 and 6. Disk 40 serves both as a brake face and ratchet wheel. Ratchet teeth 42 are integral with the periphery of disk 40. Operation of the reel is controlled by this combined brake and ratchet disk 40. Flat-faced brake linings 43 and 44 coat with opposite sides of disk 40 and operate as a brake. Brake linings 43 and 44 may be of molded Bakelite material such as "Raybestos." The brake linings are annular in shape. Brake lining 43 is stationary, being secured to base 28 of housing 30 by rivets 45. Opposite brake lining 44 is movable and fastened to flange 46 of brake shoe 50 by rivets 47.

Brake shoe 50 is manually controlled by shift member or arm 51 attached to the brake shoe by yoke 52 and pins 53, 53. An angular displacement of shift arm 51 operates threaded brake shoe 50 and its brake lining 44 towards or away from disk 40, correspondingly effecting engagement or disengagement of the braking elements. Brake shoe 50 has surface threads 54, as shown

in Fig. 5, meshing with corresponding threads on the inner surface of brake shoe case 55. Brake shoe case 55 is in the form of a ring fixedly mounted on base 28 of housing 30. Angular movement of brake shoe 50 by arm 51 thereby causes an axial movement of the brake shoe.

When brake shoe 50 is impelled towards base 28, it presses brake lining 44 against disk 40. Brake hub 35, secured to disk 40, is likewise moved axially, and disk 40 is pressed against stationary brake lining 43. Frictional engagement of the brake, comprising brake linings 43, 44 and disk 40, is effected to inhibit movement of the reel secured to brake hub 35.

The mechanism is designed to effect full engagement of the brake with a relatively small axial displacement, for example in the order of $\frac{1}{8}$ of an inch or less. The axial movement of the brake shoe between engaged and disengaged positions of the brake is, in the illustrated case, effected by a 30° rotation of shift arm 51. The brake is engaged when arm 51 is in the central position shown in solid lines in Fig. 4. The brake is designed to be fully disengaged when the arm is displaced to the right, by for example 30° , as shown in dotted lines in Figs. 1, 2 and 4 at position 51a.

An important feature of my present invention resides in providing a simple foolproof correlation of the pawl and ratchet as well as brake engagement and disengagement with the reeling-in and reeling-out operations on the antenna wire. The control of the reeling operations is effected with arm 51 operated in four positions. A substantially U-shaped slot 60 in the upper surface of housing 30 guides shift arm 51 in the shifting positions. The position of arm 51 shown in solid lines in Fig. 2 corresponds to its position shown in solid lines in Figs. 4 and 5, wherein the brake is fully engaged. This is an intermediate or rest position. When arm 51 is shifted towards the right, along channel 61, brake shoe 50 is rotated clockwise to disengage the brake, as will be described in detail hereinafter.

A pawl 65, pivoted onto brake shoe case 55 by pin 66 coacts with ratchet teeth 42 through slot 67 in case 55, as shown in Fig. 6. Spring 68, secured to brake shoe case 55, is arranged to normally mechanically bias end portion 70 of pawl 65 against ratchet teeth 42. The ratchet and pawl are accordingly normally in engaged relation. When arm 51 is operated towards the right to position 51a along channel 61, the pawl and ratchet remain engaged while the brake becomes disengaged. In position 51a, the mechanism is in condition for reeling-in any extended antenna wire portion, the pawl and ratchet holding the reel in the position in which it is stopped, as will be evident to those skilled in the art. When reeling-in is stopped, arm 51 is preferably moved back to position 51 shown in solid lines, applying the brake with the ratchet engaged.

When shift arm 51 is pressed inwardly, towards rear base 28, to position 51b in line with channel 62 as shown in Figs. 2 and 5, pawl 65 is disengaged from ratchet teeth 42. Rear upper surface 71 of pawl 65 is sloped to serve as a cam and coact with inclined surface portion 72 of yoke 52. Thus when arm 51 is moved rearwardly to position 51b, yoke 52 pivoting on pins 53, 53 presses against cammed surface 71 of pawl 65 to angularly displace pawl 65 about its pivot 66 against the biasing action of spring 68. End portion 70 of pawl 65 is moved out of engagement with ratchet teeth 42. Disengagement of the pawl

and ratchet is effective while arm 51 and yoke 52 are in the rear position along channel 62 of U-slot 60.

The position 51b of arm 51 is the intermediate one just prior to the freely reeling-out position of the reel. In position 51b the brake is still applied, preventing reeling-out though the ratchet is disengaged. The brake is disengaged when the arm is shifted to the right along channel 62 to position 51c (Fig. 2), since a clockwise rotation is imparted to brake shoe 50 impelling it outwards axially. The ratchet and pawl remain disengaged while arm 51 is in any rearward position along channel 62. A leaf spring 75 is arranged between base 28 of housing 30 and disk 40 mechanically biasing disk 40 away from stationary brake lining 43. This action serves to insure brake disengagement during reeling-out or reeling-in positions of the mechanism. When arm 51 reaches position 51c, the reel is in the position of free reeling-out.

Prior to reeling-out it is preferable to turn crank-handle 16 on pivot 18 against disk 11 for safety reasons since its rate of rotation is relatively high during unreeling. When sufficient antenna wire is extended by free unreeling, the pilot shifts arm 51 along channel 62, to the left from position 51c to 51b. The brake is thereupon applied, arresting free rotation of the reel and stopping reeling-out. The shift arm is then returned to position 51 shown in solid lines, whereupon ratchet teeth 42 are reengaged with pawl 65 and the reel mechanism is in stable rest condition.

The reeling mechanism of my present invention accordingly prevents injury to the pawl and ratchet by preventing their possible engagement at high speed rotation due to free reeling-out. The frictional brake is applied to arrest the rotation of the reel and attached ratchet disk 40 prior to the engagement of the ratchet teeth for the stable rest position. Stripping of the ratchet is inhibited. Smooth operation and transition between control positions is effected without shock or jar to the apparatus by means of the gradual frictional braking. Connection and disconnection of the brake in proper sequence is definitely assured whenever the pilot wishes to operate the shift arm; for example to change from free reeling-out to reeling-in, etc.

It is to be understood that modifications may be made in the details and arrangements of the embodiment of the invention disclosed without departing from the broader spirit and scope thereof, and accordingly I do not intend to be limited except as set forth in the following claims.

What I claim is:

1. The combination with a reel of a disk secured to said reel for rotation therewith; and braking means engageable with said disk for arresting rotation of said reel comprising an externally threaded annular member coaxial with said disk and arranged adjacent thereto, a casing surrounding said disk and having internal threads in engagement with said member, an arm secured to said member and extending through a slotted opening in said casing to permit the turning of said member angularly on its axis, the casing and member threads being arranged to axially move said member into frictional engagement with said disk when said arm is shifted in a predetermined angular direction.

2. The combination with a reel of a disk secured to said reel for rotation therewith, said disk being axially displaceable; and braking

means engageable with said disk for arresting rotation of said reel comprising an externally threaded annular member coaxial with said disk and arranged adjacent one face thereof, a brake member arranged adjacent the other disk face, a casing surrounding said disk and members, said casing having internal threads in engagement with said annular member, an arm secured to said annular member and extending through a slotted opening in said casing to permit the turning of said annular member angularly on its axis, the casing and member threads being arranged to axially move said annular member against the corresponding face of said disk when said arm is shifted in a predetermined angular direction to axially displace said disk into frictional engagement with said brake member.

3. The combination with a hand reel of a ratchet disk having ratchet teeth on its periphery and secured to said reel for rotation therewith, said reel and ratchet disk being axially displaceable; braking means engageable with said ratchet disk for arresting rotation of said reel comprising an annular member coaxial with said ratchet disk and arranged adjacent one face thereof, an arm extending from said member for turning it angularly on its axis with respect to said ratchet disk, and means for axially moving said member into frictional engagement with the face of said ratchet disk when said member is turned in a predetermined angular direction; and a pawl arranged for engagement and disengagement with said ratchet.

4. The combination with a hand reel of a ratchet disk having ratchet teeth on its periphery and secured to said reel for rotation therewith, said reel and ratchet disk being axially displaceable; braking means including a brake shoe engageable with said ratchet disk for arresting rotation of said reel comprising a member arranged adjacent said ratchet disk, an arm extending from said member for turning it angularly with respect to said ratchet disk, and means for moving said member against said ratchet disk when said member is turned in a predetermined angular direction to axially displace said ratchet disk into frictional engagement with said brake shoe; and a pawl arranged for actuation by said arm into engagement and disengagement with said ratchet teeth.

5. The combination with a reel of a disk secured to said reel for rotation therewith, said reel and disk being axially displaceable together; and braking means engageable with said disk for arresting rotation of said reel comprising a first member arranged adjacent one face of said disk, a second member arranged adjacent the other face of said disk, an arm extending from said first member for turning it angularly with respect to said disk, and apparatus including coacting portions extending from said members for axially moving said first member against said disk when said arm is shifted in a predetermined angular direction to axially displace said disk and reel in the direction for frictional engagement of said disk with said second member.

6. The combination with a hand reel of a disk secured to said reel for rotation therewith, said reel and disk being axially displaceable together; and braking means engageable with said disk for arresting rotation of said reel comprising a first member coaxial with said disk and arranged adjacent one face thereof, a stationary second member coaxial with said disk and arranged adjacent the other face thereof, an arm extending

from said first member for turning it angularly on its axis with respect to said disk, and apparatus including coacting portions extending from said members for axially moving said first member into engagement with said disk when said arm is shifted in a predetermined angular direction, to correspondingly axially displace said disk and reel in the direction for frictional engagement of said disk with said second member.

7. The combination with a hand reel of a ratchet having ratchet teeth on its periphery and secured to said reel for rotation therewith, said reel and ratchet being axially displaceable; braking means engageable with said ratchet for arresting rotation of said reel comprising a brake shoe coaxial with said ratchet and arranged adjacent one face thereof, a stationary brake shoe case coaxial with said ratchet and arranged adjacent another face thereof, an arm extending from said brake shoe for turning it angularly on its axis with respect to said brake shoe case, and coacting portions extending from said brake shoe and brake shoe case for axially moving said brake shoe against said ratchet when said brake shoe is turned in a predetermined angular direction to correspondingly axially displace said ratchet into frictional engagement with said brake shoe case; and a pawl pivoted on said stationary brake shoe case and arranged for actuation by said arm for engagement and disengagement with said ratchet teeth.

8. The combination with a hand reel of a ratchet disk having ratchet teeth on its periphery and secured to said reel for rotation therewith, said reel and disk being axially displaceable; braking means engageable with said ratchet disk for arresting rotation of said reel comprising a brake shoe and a stationary brake shoe case individually arranged adjacent said ratchet disk, brake linings carried by said brake shoe and brake shoe case on their surfaces coactable with said disk, an arm extending from said brake shoe for turning it angularly with respect to said brake shoe case, and means extending from said brake shoe and brake shoe case for moving said brake shoe against said ratchet disk when said brake shoe is turned in a predetermined angular direction, to bring said ratchet disk into frictional engagement with said brake linings; and a pawl pivoted on said stationary brake shoe case arranged for actuation by said arm for engagement and disengagement with said ratchet teeth.

9. The combination with a hand reel of a ratchet disk having ratchet teeth on its periphery

and secured to said reel for rotation therewith, said reel and disk being axially displaceable; braking means engageable with said ratchet disk for arresting rotation of said reel comprising a brake shoe and a stationary brake shoe case individually arranged adjacent said ratchet disk, brake linings carried by said brake shoe and brake shoe case on their surfaces coactable with said disk, an arm extending from said brake shoe for turning it angularly with respect to said brake shoe case, and means extending from said brake shoe and brake shoe case for moving said brake shoe against said ratchet disk when said brake shoe is turned in a predetermined angular direction, to bring said ratchet disk into frictional engagement with said brake linings; and a pawl pivoted on said stationary brake shoe case and having a cammed section arranged for actuation by said arm for engagement and disengagement with said ratchet, said arm projecting through a slot in said case and being movable along said slot for controlling the conditions of operation of said reel in a predetermined manner.

10. The combination with a hand reel of a ratchet having ratchet teeth on its periphery and secured to said reel for rotation therewith, said reel and ratchet being axially displaceable; braking means engageable with said ratchet for arresting rotation of said reel comprising a brake shoe coaxial with said ratchet and arranged adjacent one face thereof, a stationary brake shoe case coaxial with said ratchet and arranged adjacent another face thereof, an arm extending from said brake shoe for turning it angularly on its axis with respect to said brake shoe case, brake linings carried by said brake shoe and brake shoe case on their surfaces facing said ratchet, and coacting portions extending from said brake shoe and brake shoe case for axially moving said brake shoe against said ratchet when said brake shoe is turned in a predetermined angular direction to correspondingly axially displace said ratchet into frictional engagement with the lining of said brake shoe case; and a pawl pivoted on said stationary brake shoe case and having a cammed section arranged for actuation by said arm; said arm projecting through a U-slot in said case and being movable along said U-slot for controlling the conditions of operation of said reel by said ratchet and braking means whereby successive positions of said arm effect engagement and disengagement of said pawl and ratchet for reeling-in and reeling-out conditions.

WILLIAM P. LEAR.
